UNITED STATES PATENT OFFICE.

ERNEST A. TRUAX, OF INGLEWOOD, CALIFORNIA.

ELECTRIC ALARM MECHANISM.

1,168,761.

Specification of Letters Patent.

Patented Jan. 18, 1916.

Application filed May 16, 1914. Serial No. 839,034.

To all whom it may concern:

Be it known that I, ERNEST A. TRUAX, a citizen of the United States, residing at Inglewood, in the county of Los Angeles, State of California, have invented new and useful Improvements in Electric Alarm Mechanisms, of which the following is a specification.

This invention relates to an electric alarm mechanism and particularly pertains to a time controlled signal apparatus.

It is the object of this invention to provide a clock controlled mechanism by which an alarm can be sounded at any predetermined time, and in which the alarm mechanism can be set to sound either a single alarm or a number of alarms at different intervals of time.

A further object is to provide a clock controlled signal apparatus for signaling various times, and to provide a simple and effective means for setting the apparatus to operate a signal at any predetermined time, which signal apparatus is especially adapted for use for indicating times of delivery in mercantile establishments.

The invention is illustrated in the accompanying drawings, in which:

Figure 1 is a perspective view. Fig. 2 is a detail section in plan, with the contact maker removed showing the relation of the bus-bars. Fig. 3 is an enlarged detail section on the line 3—3 of Fig. 1, as seen in the direction indicated by the arrows. Fig. 4 is a horizontal section on the line 4—4 of Fig. 1. Fig. 5 is a diagram illustrating the electric circuits and connections whereby the alarm or signal apparatus is operated electrically at any predetermined time. Fig. 6 is a detail illustrating the manner of connecting the contact arms with the horizontal bus-bars.

In carrying out the present invention, a clock 10 of any suitable construction is employed; this clock having the usual dial 11 provided with the characters for indicating the time, and having the usual hour hand 12 and minute hand 13. Any suitable clock mechanism for rotating the hands 12 and 13 through the posts on which the hands are mounted may be employed as desired.

Mounted on the dial 11 and concentric with the hand supporting posts is an annular contact member 14, which connects with a conductor 15 leading to one terminal of a battery 16, the other terminal of which

battery connects with a conductor 17 leading to a bell magnet 18 of an ordinary electric bell 19; a conductor 20 leading from the bell magnet 18 to the post carrying the hand 12. 60 The hour hand 12 constitutes a conductor and mounted thereon is a brush wiper 21 adapted to traverse a series of arcuate contact members 22 arranged in a circle on the dial 11 concentric with the annular contact member 14. The contact members 22 are spaced apart and are insulated from each other and from the annular contact member 14. Twelve of these contact members are employed and are so arranged on the dial 11 70 that their terminations will be disposed on radial lines extending from the center of the dial to the hour indicating characters thereon in such manner that when the hand 12 traverses the dial the wiper 21 thereon will 75 be in contact with a separate contact member 22 between each hour indicated by the dial.

Leading from each of the contact members 22 is a conductor 23, which connects 80 with a horizontally extending bus-bar 24 mounted in a case 25 disposed at any convenient point. The bus-bars 24 are twelve in number and are superposed in relation to, and insulated from, each other; a bus-bar 24 85 being provided for each contact 22 and electrically connected therewith. The uppermost bus-bar 24 connects with the contact member 22 which is disposed between the radii leading to the hour numerals 1 and 2; 90 the next bus-bar 24 connecting with the contact 22 extending between the hour numerals 2 and 3, and so on, throughout the series.

Mounted in the case 25 and spaced from the bus-bars 24 is a series of twelve vertically extending bus-bars 26 which are spaced apart and insulated from each other and connecting with each of the bus-bars 26 is a conductor 27 which leads to and connects with a segmental contact member 28 on the 100 dial 11; a contact member 28 being provided for each vertical bus-bar 26 and arranged in a circle around the annular contact member 14 and insulated therefrom and concentric therewith. The segmental contacts 28 are of 105 such length as to extend between the radii leading from the center of the dial to the various hour indicating characters thereon, thus being twelve in number and so positioned that when the minute hand 13 is 110 traversing the dial a wiper contact member 29 thereon will be in connection with a sepa-

rate contact member 28 between each hour character on the dial. The vertical bus bar 26 at the left hand side of the case 25 electrically connects with the segmental contact 28 disposed between the radii extending through the hour characters one and two and the next bus-bar 26 electrically connects with the segmental contact 28 extending between the hour characters two and three, 10 and so on, throughout the series.

The wiper 29 bridges the gap of insulation between the segmental contacts 28 and the annular contact 14 and slidably connects with the latter; the wiper contact 29 being insulated from the hand 13 and adapted to complete electrical circuit from the annular contact member 14 to any one of the segmental contacts 28 when a vertical bus-bar 26 is electrically connected to a horizontal bus-bar 24. This connection of the vertical and horizontal bus-bars may be effected in any desired manner, whereby any one of the vertical bus-bars can be electrically connected with one or more of the horizontal bus-bars. The means for accomplishing this purpose is shown as consisting of a plurality of arms 30 formed of electrical conducting material and having bifurcated ends 31 which pivotally engage the bus-bars 24; the forked ends of the arms 30 extending in opposed grooves 32 formed on the opposite sides of the bus-bar, as particularly shown in Fig. 6.

An arm 30 is mounted on each horizontal bus-bar to extend alongside of each vertical bus-bar 26 and the arms are normally retained in a vertical position out of contact with V-shaped spring contact members 33 formed on the vertical bus-bars 26; a coiled spring 34 connecting with each arm 30 at one end and secured to the bus-bar 24 at the other operating to normally maintain the arm in its uppermost position. The outer ends of the arms 30 project through slots 35 formed in the face plate 36 on the case 25 and are bent downwardly to form plates 37 by which the arms may be manually manipulated to move them into connection with the spring contacts. The plates 37 on the end arms 30 on the bus-bars 24 extending alongside of the vertical bus-bar 26 at the left side of the case 25 are numbered from one to twelve, inclusive, from the top plate to the bottom plate to correspond 55 to the hours indicated on the clock dial and each horizontal row of the plates 37 is numbered from five to fifty-five, inclusive, in steps of five to indicate five minute divisions of the hour.

60 In the operation of the invention, when it is desired to set the device to sound an alarm at any predetermined time, an arm 30 is depressed to move it into engagement with its corresponding spring contact member 33 where it is frictionally engaged and

retained in opposition to the spring 34, thus electrically connecting the vertical bus-bar 26 and the horizontal bus-bar 24 on which the slotted arm 30 is mounted, thus placing the circuit on which the slotted bus-bars are mounted in condition to be completed on the sounding of an alarm on the closing thereof as controlled by the hands 12 and 13 of the clock.

For the purpose of illustration, let it be assumed that it is desired to sound an alarm at five minutes past seven, the arm 30 on the horizontal bus-bar 24 connecting with the conductor 23 leading to the arcuate contact member 22 disposed between the radii leading to the hour characters 7 and 8 is depressed and moved into engagement with the vertical bus-bar 26 on the conductor 27 leading to the contact segment 28 disposed between the radii extending through the hour characters one and two representing the five minute intervals on the clock dial. This operation sets the device in readiness to sound an alarm which is effected when the alarm circuit is completed by the hour hand moving the wipers 21 thereon into connection with the slotted contact 22 which completes the line from the bus-bar 24 to the bell 19 through the hour hand 12 and the conductor 20; the alarm, however, not being sounded until the minute hand 13 passes the five minute division and moves the contact 29 thereon into connection with the slotted contact 28 so as to complete the circuit from the battery 16 through the annular contact 14, contact 29 on the hand 13, contact 28 on the dial, thence through the conductor 27, bus-bar 24, arm 30, bus-bar 26, conductor 23, contacts 22 and 21, arm 12, conductor 20, through the bell 19, back to the battery and conductor 17, thus sounding the alarm.

To cut out the alarm the arm 30 through which the alarm circuit is completed will then be moved to its normal uppermost position out of connection with the spring contact 33. Likewise, the device may be set to operate at any five minute interval of time as desired, and may also be set to give a succession of alarms at any predetermined time.

This device is particularly advantageous for use in delivery departments where it is desired to make certain deliveries at predetermined times; the device being set to sound the alarm at such times so as to call the attention of the delivery clerk to his delivery record at that time. While the time set is here shown as limited to five minute intervals, it is manifest that it may be constructed to operate on shorter intervals of time by increasing the number of the contacts 28 and the corresponding bus-bars. The segments 22 are of such length that the contact 21 will be in connection therewith throughout the movement of the hour hand between

an hour mark on the dial and the succeeding hour mark so that its connection will be effected during the complete circuit of the minute hand 13 around the dial. While 5 the alarm device is here shown as consisting of a bell for sounding an audible signal, it is manifest that a visual signal in the form of an electric lamp can be employed in lieu thereof if desired.

10 What I claim is:

1. In a time controlled signal apparatus having a series of circuits closed by the hour hand, and another series closed by the minute hand, the combination of parallel spaced bus bars connected to one of the clock controlled series of circuits, keys pivoted to said bus bars, a second set of parallel spaced bus bars connected to the other clock controlled series of circuits and arranged at substantially right angles to the first mentioned set of bus bars, and spring clips on the second set of bus bars arranged to receive said pivoted keys.
2. In a time controlled signal apparatus 25 having a series of circuits closed by the

hour hand, and another series closed by the minute hand, the combination of a group of bus bars connected to one of the clock controlled series of circuits, a second group of bus bars connected to the other clock controlled series of circuits and arranged adjacent the first mentioned group of bus bars and spaced therefrom, means for connecting any one of the bus bars of one group with any one of the bus bars of the other group, 30 comprising a series of arms pivoted on each of the bus bars of one group, and a series of contact members on each of the bus bars of the other group adapted to engage said arms, and means for normally maintaining 35 said arms out of connection with the contact members on the bus bars.

In witness that I claim the foregoing I have hereunto subscribed my name this 29th day of April, 1914.

ERNEST A. TRUAX.
